MANUFACTURE OF CIGARETTES

William Frederick Maitland Edwards, Esher,
England, assignor to Filter Tips Limited,
London, England

Application December 11, 1941, Serial No. 422,576
In Great Britain January 10, 1941

12 Claims.

(Cl. 131—61)

This invention relates to cigarettes and is particularly concerned with improvements in the manufacture of filter tip cigarettes utilising a machine of the continuous rod type.

According to this invention a method is provided for the production of filter tip cigarettes by the formation of spaces for the reception of filter tips in a tobacco filling, in which tobacco is held positively by carrier members moving in succession, said members moving in a path a part of which is a straight line, the tobacco is severed between each pair of adjacent carrier members, and the severed portions are separated from one another by successive acceleration of each carrier member so that spaces are formed whilst the carrier members are processed along a part of the straight portion of the path. Preferably the portions are released from the carrier members whilst they are moving along a straight portion of the path.

The invention further includes a machine for manufacturing filter tip cigarettes which comprises a plurality of carrier members constrained to move in a path a part of which is a straight line, means such as a hopper for supplying tobacco to the carrier members, means for holding the tobacco in the carrier members, means for severing the tobacco between each pair of adjacent carrier members, and means for successively accelerating each carrier member so that spaces are formed whilst the carrier members are proceeding along a part of the straight portion of the path. Preferably also means are provided for releasing the tobacco from the carrier members whilst they are moving along a straight portion of the path.

The length of tobacco is preferably severed by means of knives such as are usually employed in tobacco machinery for cutting tobacco. The tobacco may be severed into portions corresponding in length to the tobacco portion of a filter tip cigarette and the space between adjacent severed portions may be arranged to receive a single length of filter tip material. Preferably however the severed portions will correspond in length to the combined tobacco portions of two filter tip cigarettes and the space between adjacent portions will be arranged to receive a double length of filter tip material.

The lengths of filter tip material may be arranged by any desired means in the spaces between adjacent severed tobacco portions. Preferably the severed portions are transferred from the carrier members to a moving web of paper, and lengths of filter tip material are placed upon

the web at spaced intervals by known means before, at the same time as, or after the tobacco portion is transferred to the web in such a way that the lengths of filter tip material lie in the required position.

If desired the lengths of filter tip material and the tobacco portions which are now in proximity to each other may be moved relatively to each other to effect abutment.

10 The web of paper is then folded around the tobacco portions and the lengths of filter tip material to form a continuous rod in the usual manner. Thereafter, also by known means, the rod is cut at appropriate places to form cigarettes of the desired length.

The machine may be disposed vertically, horizontally or at any desired inclination.

The invention will now be further described by way of example with reference to the accompanying drawings, in which—

Fig. 1 is a side view partly in section of a machine according to the invention,

Fig. 2 is a sectional view on the line II—II of Fig. 1,

15 Fig. 3 is a sectional view on the line III—III of Fig. 1,

Fig. 4 is a side view of a part of a modified form of the machine.

Fig. 5 is a plan view of an individual carrier,

Fig. 6 is a plan view of the cam tracks 25 taken on the line 6—6 of Fig. 3, and

Fig. 7 is an inverted plan view of the cam tracks 25' taken on line 7—7 of Fig. 2.

Referring to Figs. 1 to 3 of the drawings, a continuous rod of tobacco 1 is fed from a hopper (not shown) by the usual conveyor belt 2 which passes it under compression wheels 3 and 4 and is urged forward by movement of the compression band 4a, the tension being varied by the tension spring 4b. The tobacco is fed successively to a number of carrier members 5 each of which is provided with a peripheral groove indicated generally by the numeral 6 for receiving the tobacco and each of which moves in

40 a pair of endless tracks formed in the spaced supporting side plates 8' and 8'' and which paths each consist of two parallel straight portions 8a and 8b, one at the top and the other at the bottom of the machine joined by two semi-circular portions 8c and 8d of the same radius as a pair of sprocket wheels 10 and 11 at one end and two similar wheels 10' and 11' at the other end of the straight track portions 8a and 8b. The carrier members 5 are accelerated away from each other by cam means, more fully described here-

45 50 55

inafter, so that spaces are formed whilst the carrier members are passing along the lower straight portions $8b$ of the endless tracks.

As each carrier member reaches the beginning of the top straight parts $8a$ of the tracks it is in close proximity to the preceding carrier member, and the rod of tobacco is fed onto it whilst the flexible gripper member (more fully described hereinafter) is held open to receive it. Immediately afterwards the tobacco is firmly and positively held in the carrier member by means of this gripper member. The tobacco is thus held until it is released as described below. As the tobacco rod is moved along the path of the carriers by the means hereinafter described, a reciprocating rotating knife 7 of the usual kind severs it between each pair of adjacent carrier members. Each carrier member is provided at each end with a pair of rollers 8 , one on each side of the carrier member which, in turn, run in track portions $8a$ and as the carrier members approach the semi-circular portions $8c$ of the track portions these rollers leave the track portions $8a$ and engage with sprockets 9 of two sprocket wheels 10 and 11 positively driven by the shaft 12 . On the straight parts $8a$ and $8b$ of the path each carrier member has the drive conveyed to it by the carrier member immediately behind it by means of a cam 13 on the forward part of the carrier member immediately behind it which bears on a roller 14 carried by an arm $17a$ of a lever 17 , said lever also being connected to another roller 15 running in a cam track 16 (whose function is described hereinafter); the second mentioned roller 15 being pivotally connected to an intermediate part of the lever 17 whose other arm $17b$ is pivoted by the part 18 to the middle of the lower side of the carrier member which is being driven.

As mentioned above one part of the lever 17 is pivoted to the roller 15 which runs in the cam track 16 which follows the general outline of the endless path of the carrier members 5 until it is about to enter the lower straight line portions $8b$ of the tracks whereupon the cam track 16 moves downward and causes the roller 14 of the carrier member which is not immediately prior to this engaged by the cam 13 to run down the face $13c$ of the cam 13 on the carrier member immediately behind it (the action will be seen clearly by considering the cam members $13a$ and $13b$) thus giving the carrier member $5a$ an acceleration away from the carrier member $5b$ immediately behind it, the acceleration being such that the speed of a carrier member $5a$ becomes equal to the linear speed of the paper web to 19 referred to below and causing a space 18 to form. At a predetermined point $18''$ the tobacco 1 is ejected from the carrier member by means hereinafter described and it is then deposited upon the moving web of paper 19 fed from a bobbin (not shown in the drawings) in the usual manner.

At the point $18''$ at which the tobacco is released the cam track 16 moves upwards with resulting deceleration of the carrier members and this continues until the track 16 reaches its normal spacing inwardly of the endless path of the carriers 5 .

The action of the device by which the tobacco is ejected on to the paper is as follows:

The peripheral groove 6 of the carrier member 5 is formed by a layer of flexible material 20 preferably a fabric constituting a gripper member. The ends of the fabric are firmly held by

opposed metal jaws 22 which are normally urged together by springs 23 . At the point at which the tobacco is to be ejected the jaws 22 are drawn apart by the motion of a pair of gripper carrier rollers 24 connected respectively to the opposed jaws in passing over arcuate cam tracks 25 . The drawing apart of the jaws causes the flexible material 20 to tauten and eject the tobacco 1 . After ejecting the tobacco the gripper carrier rollers 24 reach the end of the cam tracks 25 . The jaws 22 are then urged together by the action of the springs 23 and remain closed until they reach the arcuate cam tracks $25'$ which act on the gripper carrier rollers 24 to open the jaws 22 to receive the tobacco. When the rollers 24 reach the end of the arcuate cam tracks $25'$ the jaws 22 are urged together by the springs 23 and grip the tobacco rod 1 .

The paper 19 is gummed at spaced intervals by a gumming unit of the usual kind (not shown in the drawings) and wads 26 of twice the length required for a filter tip cigarette are deposited on the gummed portions of the paper from a wad hopper also of the usual kind (not shown in the drawings) leaving a space 27 between successive wads of substantially the same length as that of the cut sections 35 of the tobacco rod held in the carrier members. A guide tape 28 serves to hold and align the wads on the paper and a heated platform 29 dries the gum and fixes the wads to the paper. The timing is such that each carrier member at the time it releases the tobacco is travelling at the same linear velocity as the paper and so that the released portions of tobacco are deposited between the wads. The whole assembly then passes through a garniture of the usual kind (not shown in the drawings) and the continuous cigarette rod thus formed is divided into individual cigarettes by a knife (not shown in the drawings) in the usual manner.

It will be understood that the shape of the cam track 16 ensures that each carrier member is accelerated and decelerated in turn and that the gaps will always occur in the same positions.

Referring to Fig. 4 of the drawings which shows another means for conveying the drive from one carrier member to the next: In this modified machine, two links 30 and 31 are pivoted by the pivot 32 to the middle of the underside of each carrier member 5 , the forward link 31 of one member being pivotally connected to the rear link 30 of the carrier member immediately in front by a pivot 33 carrying a cam roller 34 moving in the cam track $16'$ of the configuration shown in the drawings.

Furthermore other releasing means for the tobacco may be employed, for example the means described in my applications Serial Nos. 344,581 and 352,460, which have issued as Patents 2,335,747 dated November 30, 1943, and 2,291,890 dated August 4, 1942, respectively.

I claim:

1. In a method for the production of filter tip cigarettes the steps of moving a continuous length of tobacco in a path a part of which is a straight line, severing the said length into portions, separating the portions from one another by successive acceleration of the portions so that spaces are formed between the portions whilst they are proceeding along a part of the straight portion of the path, and thereafter transferring the portions successively from the straight portion of the path to a moving web of paper carrying a plurality of lengths of filter tip material in

such a way that each tobacco portion is disposed between two lengths of filter tip material to form an assemblage of alternate tobacco portions and portions of filter tip material.

2. A method for the production of filter tip cigarettes which comprises moving a continuous length of tobacco in a path a part of which is a straight line, severing said length into portions, separating the portions from one another by successive accelerations of the portions so that spaces are formed between the portions whilst they are proceeding along a part of the straight portion of the path, thereafter transferring the portions from the straight portion of the path to a moving web of paper carrying a plurality of lengths of filter tip material in such a way that each tobacco portion is disposed between two lengths of filter tip material to form an assemblage of alternate tobacco portions and portions of filter tip material, wrapping and securing the web of paper around the assemblage to form a continuous rod and dividing the said rod into filter tip cigarettes.

3. In a machine for manufacturing filter tip cigarettes the combination of a plurality of movable carrier members, means adapted to constrain said members to move in a path a part of which is a straight line, means for supplying tobacco to the carrier members, means for holding the tobacco in the carrier members, means for severing the tobacco between each pair of adjacent carrier members, and means for successively accelerating each carrier member so that spaces are formed therebetween whilst the carrier members are proceeding along a part of the straight portion of the path.

4. In a machine for manufacturing filter tip cigarettes the combination of a plurality of movable carrier members, means adapted to constrain said members to move in a path a part of which is a straight line, means for supplying tobacco to the carrier members, means for holding the tobacco in the carrier members, means for severing the tobacco between each pair of adjacent carrier members, means for successively accelerating each carrier member so that spaces are formed therebetween whilst the carrier members are proceeding along a part of the straight portion of the path, and means for releasing the tobacco from the carrier members whilst they are passing along a straight portion of the path.

5. In a machine for manufacturing filter tip cigarettes the combination of a plurality of movable carrier members, means adapted to constrain said members to move in a path a part of which is a straight line, means for supplying tobacco to the carrier members, means for holding the tobacco in the carrier members, means for severing the tobacco between each pair of adjacent carrier members, means for successively accelerating each carrier member so that spaces are formed therebetween whilst the carrier members are proceeding along a part of the straight portion of the path, and means for positively ejecting the severed portions of tobacco from the carrier members.

6. In a machine for manufacturing filter tip cigarettes the combination of a plurality of movable carrier members, means adapted to constrain said members to move in a path a part of which is a straight line, means for supplying tobacco to the carrier members, means for holding the tobacco in the carrier members, means for severing the tobacco between each pair of adjacent

carrier members, means for successively accelerating each carrier member so that spaces are formed therebetween whilst the carrier members are proceeding along a part of the straight portion of the path, and means for transferring the severed portions of tobacco from the carrier members to a moving web of paper carrying a plurality of lengths of filter tip material thereon in such a way that the lengths of filter tip material and the portions of tobacco are disposed alternately.

5 7. In a machine for manufacturing filter tip cigarettes the combination of a plurality of movable carrier members, means adapted to constrain said members to move in a path a part of which is a straight line, means for supplying tobacco to the carrier members, clamping means for holding the tobacco in the carrier members, means for severing the tobacco between each pair of adjacent carrier members, means for successively accelerating each carrier member so that spaces are formed therebetween whilst the carrier members are proceeding along a part of the straight portion of the path, and means for releasing the severed portions of tobacco at a pre-determined point in a straight portion of said path.

15 8. In a machine for manufacturing filter tip cigarettes the combination of a plurality of movable carrier members, means adapted to constrain said members to move in a path a part of which is a straight line, means for supplying a continuous length of tobacco to the carrier members, clamping means for holding the tobacco in the carrier members, means for severing the length of tobacco between each pair of adjacent carrier members, means for successively accelerating each carrier member so that spaces are formed therebetween whilst the carrier members are proceeding along a part of the straight portion of the path, and means for positively ejecting the severed portions of tobacco at a pre-determined point in a straight portion of said path on to a moving web of paper carrying a plurality of lengths of filter tip material thereon in such a way that the lengths of filter tip material and the portions of tobacco are disposed alternately.

25 9. In a machine for manufacturing filter tip cigarettes the combination of a plurality of movable carrier members, each of said carrier members having a peripheral channel therein made of flexible material, means adapted to constrain said members to move in a path a part of which is a straight line, means for supplying a continuous length of tobacco to the carrier members, spring means for holding the flexible material in the shape of a peripheral channel enclosing the tobacco, means for severing the length of tobacco between each pair of adjacent carrier members, means for successively accelerating each carrier member so that spaces are formed therebetween whilst the carrier members are proceeding along a part of the straight portion of the path, and cam means adapted to open successively each of said peripheral channels against the action of the spring means so as to release the severed portions of tobacco at a predetermined point in a straight portion of said path.

30 10. In a vertically disposed machine for manufacturing filter tip cigarettes the combination of a plurality of movable carrier members, means adapted to constrain said members to move in a path a part of which is a straight line, means for supplying a continuous length of tobacco to the

carrier members, means for holding the tobacco in the carrier members, means for severing the length of tobacco between each pair of adjacent carrier members, means for successively accelerating each carrier member so that spaces are formed therebetween whilst the carrier members are proceeding along a part of the straight portion of the path, and means for releasing the tobacco from the carrier members whilst they are moving along a straight portion of the path.

11. In a machine for manufacturing filter tip cigarettes the combination of a plurality of movable carrier members, means adapted to constrain said members to move in a path a part of which is a straight line, means for supplying a continuous length of tobacco to the carrier members, means for holding the tobacco in the carrier members, means for severing the length of tobacco between each pair of adjacent carrier members, cam means for successively accelerating each carrier member so that spaces are formed therebetween whilst the carrier members are proceeding along a part of the straight portion of the path, and means for releasing the tobacco from the carrier members whilst they are moving along a straight portion of the path.

12. A vertically disposed machine for manufacturing filter tip cigarettes which comprises a plurality of movable carrier members each having therein a peripheral channel made of

flexible material and each provided with rollers adapted to run in a track consisting of two parallel straight portions joined by two semi-circular portions, means for supplying a continuous length of tobacco to said carrier members, spring means for holding said peripheral grooves in a normally closed position enclosing the tobacco, a knife for severing the length of tobacco between each pair of adjacent carrier members, cam means for successively accelerating each carrier member so that spaces are formed therebetween whilst the carrier members are proceeding along a part of the straight portion of the track, cam means adapted to open successively each of the said peripheral channels against the action of the spring means so as to eject positively the severed portions of tobacco, means for supplying a moving web of paper having lengths of filter tip material disposed thereon at spaced intervals, the arrangement being such that the ejected portions of tobacco fall on to the web of paper so that each tobacco portion is disposed between two lengths of filter tip material to form an assemblage of alternate tobacco portions and portions of filter tip material, wrapping and securing means for wrapping and securing the web of paper around the assemblage to form a continuous rod and a knife for dividing the said rod into filter tip cigarettes.

30 WILLIAM FREDERICK MAITLAND EDWARDS.
